(57) **CLAIM**

The ornamental design for an electric motor including a ferromagnetic yoke and embedded flat magnets, as shown and described.

DESCRIPTION

FIG. 1 is a perspective view of an electric motor including a ferromagnetic yoke and embedded flat magnets showing my new design;

FIG. 2 is a side elevational view thereof; and,

FIG. 3 is an end elevational view thereof, the opposite end being a mirror image.

The dashed broken lines of a shaft illustrate portions of the design that form no part of the claim.
